Application July 9, 1937, Serial No. 152,783

3 Claims. (Cl. 311—39)

The present invention relates to stands and more particularly to such stands as are used by bookkeepers. Among the objects of this invention are to provide a stand which is readily adjustable for use in different positions of height adjustment; to provide a stand which will normally retain itself in its highest position of adjustment, after being put in such position, regardless of any ordinary loads; to provide a structure 5 of the character indicated which is normally self-sustaining in any adjusted position under a given load; and such further objects, advantages, and capabilities as will hereafter appear and as are inherent in the construction disclosed herein. 10 Our invention further resides in the combination, construction, and arrangement of parts illustrated in the accompanying drawings and, while we have shown therein what is now regarded as the preferred embodiment of this invention, we 15 desire the same to be understood as illustrative only and not to be interpreted in a limiting sense.

In the drawings annexed hereto and forming a part hereof:

Fig. 1 represents a plan and Fig. 2 a front elevation of a stand embodying our present invention;

Fig. 3 represents a side elevation, extended to full height, and Fig. 4 a side elevation, lowered as much as possible, of this invention;

Fig. 5 represents a horizontal section taken approximately along the plane indicated by the line 5—5, Fig. 2;

Fig. 6 represents a fragmentary vertical section taken approximately along the plane indicated by the line 6—6, Fig. 3;

Fig. 7 represents a fragmentary vertical section showing the latching mechanism in detail; and

Fig. 8 represents a cross section approximately along the plane indicated by the line 8—8, Fig. 3.

Reference will now be made in greater detail to the annexed drawings for a more complete description of this invention. This stand comprises relatively movable top and bottom sections supported on casters and provided with means 40 for moving the two sections relatively to each other and for holding them in relatively adjusted position when the stand is extended to its full height. Besides the casters 1, the bottom or base section comprises the tray 2 and the leg sections 3 and 4. The top section comprises the upper tray 5 and the upper leg sections 6 and 7. The top section also comprises the bars 8 which are bent, as shown in Figs. 3 and 4, and fastened, at their ends, to the downwardly extending flange 55 of the top 5.

The lower leg sections 3 and 4 have their longitudinal edges turned in, as indicated at 9 in Fig. 8, to form a channel within which the upper leg sections 6 and 7 are received and are vertically slidable during adjustment of the height of the stand. Brackets or arms 10 are secured to a pair of leg sections 3 and have the ends of a U-shaped handle 11 secured thereto, as indicated at 12. Links 13 connect the opposite arms of the handle 11 to the bars 8 and furnish force-transmitting means whereby force applied to the handle 11 may be transmitted to the top section of the stand. The tray 5 is connected by means of springs 15 to the handle 11. It will therefore be apparent that, as the handle is lifted from the position shown in Fig. 4 toward that shown in Fig. 3, the top section will move upwardly and the springs 15 will contract, as shown by a comparison of Figs. 3 and 4. Therefore, the tendency to elongate the springs 15 when the top section 20 moves downwardly results in these springs tending to counterbalance a weight placed on the tray 5.

On the front of the stand are mounted a pair of brackets 16 which cooperate with the latch 17, actuated toward holding position by a spring 18. A hinge 19 connects the latch 17 to the handle member 11. This handle member is provided with a loop 20 intended to be grasped by the hand when the handle is being operated. A finger-piece 21 is secured to the latch 17 and serves as means for unlatching the handle so the top may be removed. Arms 22 and 23 furnish means whereby the spring 18 may be attached to the handle member 11 and latch 17. When one 30 grasps the grip or hand-piece 20 with the right hand and presses with the thumb against the finger-piece 21, he stretches the spring 18, turning the latch 17 on its hinge 19 and freeing the latch from the brackets 16, which makes it possible to move the handle member 11 downwardly. When the handle is unlatched and moved downwardly from the position shown in Fig. 3, the links 13 are pulled downwardly, thus causing the bars 8 to move downwardly and with these 40 travel the tray 5 and leg sections 6 and 7. The pivot 8a travels downwardly at substantially the same rate as the pivot 11a but the lower end of spring 15 moves downwardly more rapidly than does its upper end. This, therefore, causes elongation of 45 the springs 15 and a consequent tendency on the part of the springs to cause the forward end of the handle to move upwardly. The stronger the springs 15 the greater will be the tendency to hold the tray 5 in its upper position.

It will of course be understood that the specific description of structure set forth above may be departed from without departing from the spirit of this invention as set forth in this specification and the appended claims.

Having now described our invention, we claim:

1. A table comprising a base section including substantially vertical guides, a top section which may be elevated from the base section, said top section comprising a top or tray table, members depending therefrom slidably engaging said guides, a lever pivoted to one side of the base section, extending below the top or tray table and to the opposite side of the base section, loose connection means connecting the top section and said lever intermediate the length of the latter, said loose connection means allowing pivotal motion of the lever and concurrent vertical reciprocation of the top section, and a tension spring connected to the top section and to the lever at a point between the connection of the lever to the connection means and the free end of the lever whereby, upon pivotal motion of said lever, the points of connection of said tension spring to the top section and to the lever both move in the same direction.
- 10 2. A table comprising a base section including substantially vertical guides, a top section which may be elevated from the base section, said top section comprising a top or tray table, members depending therefrom slidably engaging said guides, a lever pivoted to one side of the base section, extending below the top or tray table and to the opposite side of the base section, a connecting link pivoted to said lever intermediate the length thereof and

to said top section, said link being positioned approximately parallel to said vertical guides, and a tension spring connected to the top section and to the lever at a point between the connection of the lever to the link and the free end of the lever whereby, upon pivotal motion of said lever, the points of connection of said tension spring to the top section and to the lever both move in the same direction.

- 15 3. A table comprising a base section including substantially vertical guides, a top section which may be elevated from the base section, said top section comprising a top or tray table, members depending therefrom slidably engaging said guides, a pair of levers both pivoted to one side of the base section for movement thereof respectively approximately in the planes of the two sides adjacent to said one side of the base section, said levers extending below the top or tray table and to the side of the base section opposite said one side, loose connection means connecting the top section and each of said pair of levers intermediate the length of each of said levers, said loose connection means allowing pivotal motion of said levers and concurrent vertical reciprocation of the top section, and a tension spring connected to the top section and to the levers at points between the connection of the levers to said loose connection means and the free ends of said levers whereby, upon pivotal motion of said levers, the points of connection of said tension spring to the top section and to the levers both move in the same direction.
